No. 15,039

UNITED STATES PATENT OFFICE.

JOSEPH LOEB, OF PHILADELPHIA, PENNSYLVANIA.

DESIGN FOR A CHENILLE PENDANT.

SPECIFICATION forming part of Design No. 15,039, dated June 3, 1884.

Application filed March 24, 1884. Term of patent 3½ years.

To all whom it may concern:

Be it known that I, JOSEPH LOEB, a citizen of the United States, residing in the city and county of Philadelphia, State of Pennsylvania, 5 have invented and produced a new and original Design for Pendants, of which the following is a specification, reference being had to the accompanying photographic illustration, forming part thereof.

10 The leading feature of my design for a pendant, generally known as a "chenille pendant," consists of bulbs or swells attached to a crescent-shape body on the horns thereof.

15 A represents the body of the pendant, the same being of crescent shape.

B represents two bulbs or swells attached to the body at the upper part thereof, or the horns of the same, and projecting outwardly therefrom, the whole forming an attractive pendant. 20

I claim—

The design for a pendant herein shown and described, the same consisting of a crescent-shaped body and bulbs on the horns thereof.

JOS. LOEB.
